D12-133. OR D 11,954 EX

No. 11,954.

Aug. 24 - 1880.

UNITED STATES PATENT OFFICE.

FREDERICK W. PORTER, OF SPRINGFIELD, VERMONT.

DESIGN FOR A CARRIAGE-BODY.

SPECIFICATION forming part of Design No. 11,954, dated August 24, 1880.

Application filed July 17, 1880. Term of patent 7 years.

To all whom it may concern:

Be it known that I, FREDERICK W. PORTER, of Springfield, in the county of Windsor and State of Vermont, have invented and produced 5 a new and original Design for Carriage-Bodies, of which the following is a specification, reference being had to the accompanying photographic representation, forming part thereof.

The photographic print is a perspective view 10 of my carriage-body.

The design, as will be seen from an inspection of the photograph, consists as a leading feature in open-work angular and radiating sides and ends.

1 A, the base of the carriage-body, is rectangular in form or general contour. Into the upper surface of this base, and near the edges of its sides and ends, and flaring outwardly from it, are spindles B. These spindles are cylindrical in form, and, besides flaring from the base A, they are inserted at such angles to each other as would cause them to converge if these angles were carried downward to a single point. The upper ends of the spindles of the sides 20 are received into cylindrical horizontal and parallel bars C and D, the ends of these bars projecting beyond the last one of their several connecting-spindles, as at a. The spindles B,

at one part, E, of the design, are carried upward somewhat farther than at the other part, 30 F, and the spindles at the head G and foot H are received at their upper ends into head and foot pieces I and J, respectively, which have ornamental outlines, the entire design of the carriage-body presenting to the eye, by the 35 combined effect of its outlines, a light, open-work, and airy carriage-body formed of straight lines, and without curves, excepting the outlines of the head and foot pieces I and J before named.

Having now described my design for a carriage-body, what I claim as new, and desire to secure by Letters Patent, is—

The design for a carriage-body herein shown and described, the same consisting of the flaring and converging spindles B at their lower ends springing from a base, A, of rectangular form, and at their upper ends received into parallel and cylindrical horizontal bars C and D, and head and foot pieces I and J, with ornamental outlines.

FREDERICK W. PORTER.
